United States Patent Office

Des. 234,269
Patented Feb. 4, 1975

234,269

MOTION PICTURE PROJECTOR OR THE LIKE

Dianne B. Ainslie, 901 Elmgrove Road,
Rochester, N.Y. 14650

Filed July 16, 1973, Ser. No. 379,904

Term of patent 14 years

Int. Cl. D16—02

U.S. Cl. D61—1 K

FIG. 1

FIG. 2

FIG. 3

FIG. 1 is a top, front, and left side perspective view of a motion picture projector showing my new design with the cover on;

FIG. 2 is a top, front and right side perspective view thereof with the cover removed;

FIG. 3 is a bottom, rear, and right side perspective view thereof.

I claim:

The ornamental design for a motion picture projector or the like, as shown and described.
